METHOD OF LASTING TOES.

1,124,958.

Specification of Letters Patent.

Patented Jan. 12, 1915.

Original application filed December 17, 1910, Serial No. 597,851. Divided and this application filed July 26, 1912. Serial No. 711,648.

To all whom it may concern:

Be it known that I, ARTHUR L. RUSSELL, a citizen of the United States, residing at Hyde Park, in the county of Norfolk and 5 State of Massachusetts, have invented certain Improvements in Methods of Lasting Toes, of which the following description, in connection with the accompanying drawings, is a specification, like reference characters on the drawings indicating like parts in the several figures.

This invention relates to the manufacture of boots and shoes and particularly to the operation of lasting and temporarily securing 15 the shoe upper. A present general practice is to overwork the upper into lasted position about the toe end of the last by wipers that have acting edges shaped to embrace the toe portion of the shoe and lay the upper 20 over the margin of the innersole. The innersoles of welt and turn shoes are provided with upstanding lips or other formations that present a shoulder against which the upper is lasted. A binder of wire or other 25 continuous material is employed to secure the upper in lasted position by anchoring it at one end and drawing it tightly about the upper around the toe to bind it against the shoulder of the innersole after which it is 30 anchored under tension.

An object of the present invention is to bind the toe without the use of anchor tacks and a further object is to improve the binding of the upper, which frequently slips to 35 some extent under the binding wire, and another object is to improve that portion of the lasting which includes the shaping of the upper on the margin of the shoe bottom by the stiffening and shrinking action of 40 heat on the overlasted margin of the upper. In one aspect of the invention the action of the heat may be sufficient to render the shaping of the upper in its lasted position so complete and permanent that no binding 45 means need be applied to retain the shaped upper in position for permanent fastening to the shoe sole or innersole.

In securing the first-mentioned objects I prefer to use a binder, which forms the subject-matter of another divisional application, and which is provided with an adhesive 50 that will enable it to stick to the upper. It will be readily understood that the binder holds the upper over the end of the toe

largely by confining it in overwiped position 55 and that for serving this purpose the binder may be caused to adhere at its ends only at the sides of the toe. Preferably, however, the binder will be made to adhere to the shoe throughout the length of the binder and by 60 sticking to the upper it will prevent the upper from slipping under it at any point.

The adhesive used on the binder may be of any suitable kind although it will advantageously be one of the varieties that are 65 non-sticky while dry and at ordinary temperatures and are rendered sticky by heat, and the invention may be practised with the aid of lasting apparatus which includes means for heating the binder to cause the 70 adhesive to stick to the shoe upper. This may be accomplished by special heated tools as, for example, tools that act only on the end portions of the binder back of the wipers and serve primarily for binder and 75 anchoring purposes but I prefer to heat the wipers themselves. By the use of heated wipers the binder may be caused to adhere to the upper throughout its length and to hold the upper more firmly. Also the heated 80 wipers serve better to form the upper over the innersole margin and to iron out any wrinkles which may require treatment. Of course the heated wipers or other devices 85 will not be used at a temperature that will injure the particular leather of the shoes being made or disadvantageously affect the portion of the shoe treated with the heat, but I have discovered that a leather shrinking heat may be applied, as distinguished 90 from a leather softening heat, which will contract and, particularly under pressure, more or less stiffen the flange of the upper that is over the innersole margin. Such shrinking and stiffening action leaves the 95 flange of the upper more fixedly or permanently set in lasted or molded position than is possible by pressure accompanied by such moderate heat as will merely warm and soften the upper and render it pliable.

100 The drawings include an illustration of an apparatus covered by application Ser. No. 597,851, filed Dec. 17, 1910 from which this application is a division. This apparatus may be used in practising this invention, 105 or the invention may be practised by hand or with the aid of any other suitable apparatus.

In the drawings, Figure 1 is a perspective

view of the binder 30 which I prefer to use; Fig. 2 shows the binder being applied to a shoe during the operation of lasting by the use of heated toe embracing wipers 6 and binder end rubbers 20 which are eccentrically pivoted on the wipers and are also connected with actuating mechanism 23, 24, 26, 28, 29, 22, 27 by which they may be turned independently of the wipers actuating means 12, 10 15 in a direction to rub the binder ends toward the heel of the shoe. Fig. 3 shows the shoe at the end of the operation with the upper worked over the bottom of the toe portion of a last and molded with heat into position 15 to be fastened and an adhesive coated binder applied to the molded and heated upper, the binder being caused by heat to adhere to the upper and maintain it in lasted position.

In practising the invention with the aid 20 of apparatus herein shown the wipers 6 will be used as is customary to work the upper into lasted position and because of their heated condition, as by gas flames 25, they will smoothly iron and shrink the upper.

25 Then the wipers will be partially backed away from the shoulder 32 of the innersole, or from the upper which they have pressed against the shoulder, and the strip or strand 30 of binding material coated on its back 30 with adhesive, preferably one which is non-adhesive at ordinary temperatures but will be rendered tacky by heat, will be placed about the toe in the space opened up by backing off the wipers. This strip may ad-

35 vantageously be thin fabric or paper rendered stiff by the adhesive and capable of standing on edge with the adhesive against the upstanding upper. If the upper has become heated by the wipers, that heat may be

40 sufficient to cause the binder to adhere to the upper. Preferably, however, the binder will be further heated, particularly at its end portions. For this purpose the end rubbers 21 may be used and advantageously

45 the heated wipers will be advanced, after the strip 30 has been applied, to force the binder into intimate contact with the upstanding upper and to heat and soften the adhesive to make it stick. The binder rub-

50 beres may advance with the wipers, as by being carried on them, Fig. 3, to rub rearwardly and take out any slack from the binder that is developed by the advance of the wipers in pressing the binder against

55 the upstanding flange of upper. The binder heating means may remain in contact with the binder for the necessary time to allow the heat to act and then be, preferably, partially backed away where the wipers con-

60 tinue to hold the upper from slackening back while the adhesive sets into holding condition. It is to be understood that while an adhesive-coated binder is preferably used and while the adhesive is preferably heated 65 to make it stick, this invention in some of

its aspects is broad enough to cover the use of any binder whether or not it needs the application of heat in its use. The upper does not require to be bound with the same security after having been overworked 70 and molded by the use of heated wipers, because the molding heat has been effective in shrinking the upper over the innersole and giving it a substantial set.

The advantage which is obtained from 75 shrinking the fringe of the upper, as herein described, after it has been folded in over the edge of the last bottom is of special importance. The shrinking of this overlaid portion of the upper at this time not only 80 leaves the shoe in better shape around the toe so that the welt may lie snugly when attached but also the inturned upper, by reason of its contraction or shrinking, has less tendency to slack back over the edge of the 85 shoe when the wipers are withdrawn. If the heated wipers are allowed to remain over the upper long enough, light upper material in some classes of work becomes so permanently formed that the shoe can be 90 welted without binding in the toe.

In the described procedure the maximum heating and shrinking action may be given to the flange from near the edge of the shoe, where the surface curves down, to near the 95 shoulder, the insertion of the binder preventing the stock along the line where the inseam stitching is to come from being stiffened by heat. In case the maximum effect of the heat on the flange extends around the 100 curved end of the toe on a line shorter than the edge line of the innersole, the portion shrunk or contracted in that way will do much toward preventing the stock from slackening back across said edge line. Such 105 slackening back is caused by the elasticity of the upper leather which is drawn under tension over the toe and gathered in over the margin of the insole. If the portion so gathered in, or a continuous line thereof extending around the toe, be shrunk and its 110 elasticity and pliability thereby reduced, as may be done by the use of heat in the manner described, it will of course restrain the upper from drawing outwardly over the 115 edge of the toe.

An adhesive coated toe binder which required simply to be moistened has been used with good results without heat, and a binder, the adhesive of which is of proper quality, 120 can be made to stick satisfactorily by pressure without the application of heat or moisture.

It will be noted that in accordance with 125 this method the upper is secured in lasted position without necessarily penetrating the innersole or the last and that this is done by attaching together, that is to one another, the several portions of the upper after they have been gathered inwardly over 130

the convex edge of the last, the line of attachment being located at a distance inside the curved edge line of the toe and thereby being shorter than said edge line so that 5 the gathered portions are confined in lasted position.

That improvement herein disclosed in 10 shoes produced by the practice of this method is claimed in co-pending application Ser. No. 802,157, and that improvement in toe binders herein disclosed is claimed in co-pending divisional application Ser. No. 711,647.

Having explained the nature of the present 15 invention, I claim as new and desire to secure by Letters Patent of the United States:—

1. That improvement in methods of making shoes which consists in working an upper over a last, molding it into position to 20 be fastened with a degree of heat sufficient to shrink the edge of the upper on a curved line extending around the margin of the shoe bottom at the toe, and applying to the upper so molded and heated a binder coated 25 with an adhesive which is caused by the heat to adhere to the upper and maintain it in lasted position.

2. That improvement in methods of making 30 shoes which consists in wiping an upper over the toe end portion of a last, heating the upper so wiped over, applying an adhesive-coated binder to the outer side of the overworked and heated upper, pressing the binder into holding position and heating it 35 to cause it to adhere.

3. That improvement in methods of making 40 shoes which consists in working an upper over the end portion of a last and forming it into position to be secured upon the shoe bottom, applying an adhesive binder upon the formed upper about the shoe end, applying tension to the binder ends, and then applying pressure to the binder throughout its length and additional tension 45 to the ends to take up any slack developed by such pressure.

4. That improvement in methods of making 50 shoes which consists in working an upper over a last and molding it into position over an innersole with a degree of heat sufficient to shrink the edges of the upper, maintaining the heat with pressure to shrink the upper that is on the innersole, and applying to the upper so molded and shrunk a binder to maintain it in lasted position.

5. That improvement in methods of making 60 shoes which consists in forcing an upper into lasted position over the shoe bottom about a curved end portion of a last and shaping the upper that is on the shoe bottom by the application of a sufficient degree of heat accompanied by pressure to shrink that portion of the upper, and maintaining the upper under pressure and heat until it has 65 set in lasted position upon the shoe bottom.

6. That improvement in methods of making 70 shoes which consists in working the edge portion of the upper over the last bottom, and then shrinking the edge portion of the upper material in its overworked position relatively to the remaining portion of the upper.

7. That improvement in methods of making 75 shoes which consists in working the edge portion of an upper over an end portion of the last, then shrinking the edge portion of the upper material where it overlies the last bottom relatively to the remaining portion of the upper, and imparting to the shrunken portion of the upper material a permanent 80 set.

8. That improvement in methods of making 85 shoes which consists in working the edge portion of elastic upper leather over the end portion of a last to shape it to the last, and then reducing the elasticity of the overworked portion on the edge of the last relatively to the remaining portion of the upper leather to lessen its tendency to react.

9. That improvement in methods of making 90 shoes which consists in working an upper over the toe portion of a last into position upon the innersole to be fastened, and then applying a long narrow binding strip to the curved marginal edge of the shoe bottom around the toe and attaching the binder throughout its length to the outer surface only of the overworked upper which it is to hold.

10. That improvement in methods of making 100 shoes which consists in working an upper over the toe portion of a last into position against the upstanding lip of a welt shoe innersole and fastening a long narrow binding strip at its ends and also at points intermediate between its ends to the outer surface only of the upper which has been lasted against the innersole lip whereby the upper around the end of the toe is held from slackening back by means of a direct connection of the lasted over parts thereof with the binder.

11. That improvement in methods of making 110 shoes which consists in working an upper over the toe portion of a last into position upon the innersole to be fastened, applying a long narrow binding strip to the curved marginal edge of the overlasted upper upon the shoe bottom and attaching at its ends and also at intermediate portions the said binder by pressure to the upper alone without either engaging or penetrating the innersole.

12. That improvement in methods of making 120 shoes which consists in working an upper over the toe portion of a last into position and then attaching a long narrow binding strip to the curved marginal edge of the overworked upper around the end of the toe and also at the sides of the toe along 130

- a line determined by the extent to which the upper is overdrawn in lasting, and securing the binder exclusively to the upper without attaching it to the innersole or to the last.
5. 13. That improvement in methods of making shoes which consists in working an upper over the convex toe end of a last and gathering it together over the bottom face of the last at a distance from the edge of 10 the shoe and then attaching together portions of the outer faces only of the several parts of said gathered upper along a line extending uninterruptedly around the toe and located inside the convex shoe edge and 15 shorter than the toe edge line.
14. That improvement in methods of making welt shoes which consists in working the edge portion of an upper over the feather and against the lip of a welt inner- 20 sole upon a last bottom, and then shrinking the upper overlying the feather of the innersole on a curve extending around the toe relatively to the upper on the sides faces of 25 the last and portions of the upper extending above the innersole lip.
15. That improvement in methods of making welt shoes which consists in working the edge portion of an upper over the feather and against the lip of a welt inner- 30 sole upon a last bottom, applying a long narrow adhesive coated binding strip to the upper so worked over the marginal portion of the shoe bottom, and pressing the binding strip into holding position and heating 35 it to cause it to adhere.
16. That improvement in methods of making welt shoes which consists in working the edge portion of an upper over the feather and against the lip of a welt inner- 40 sole upon a last bottom, applying a long narrow adhesive coated binding strip to the upper so worked over the marginal portion of the shoe bottom, and pressing the binding strip into holding position along the 45 curve surrounding the toe and causing the binding strip to adhere to the upper along such curve between the ends of the strip to prevent the upper from slipping and slackening back under it.
17. That improvement in methods of 50 making welt shoes which consists in working the edge portion of an upper over the feather and against the lip of a welt inner-sole upon a last bottom, and cementing to the overworked upper material exclusively 55 between the lip and the edge of the inner-sole a binding strip extending from one side of the toe around the end of the toe to the other side of the toe.
18. That improvement in methods of 60 making welt shoes which consists in working the edge portion of an upper over the feather and against the lip of a welt inner-sole upon a last bottom and cementing to the portion of the upper which stands 65 against the rib of the innersole a long narrow binding strip placed on edge with a side face against said upstanding upper material.
19. That improvement in methods of 70 making shoes having channeled and lipped or shouldered innersoles or soles which consists in working the upper materials over the last and against the upstanding face of the lip or shoulder, cementing a long nar- 75 row binding strip exclusively to the over- worked upper materials with one edge up- standing against said upstanding upper ma- terials in position to be included in the seam which is to connect the upper materials per- 80 manently to the lip or shoulder of the inner- sole or sole.
- In testimony whereof I have signed my name to this specification in the presence of two subscribing witnesses.
